UNITED STATES PATENT OFFICE.

WILLIAM J. SMITH, OF BROOKLINE, NEW HAMPSHIRE.

BARREL-HEAD CUTTER.

SPECIFICATION forming part of Letters Patent No. 271,984, dated February 6, 1883.

Application filed September 2, 1882. (No model.)

To all whom it may concern:

Be it known that I, WM. J. SMITH, a citizen of the United States, and a resident of Brookline, in the county of Hillsborough and State of New Hampshire, have invented a new and valuable Improvement in Barrel-Head Cutters; and I do hereby declare that the following is a full, clear, and exact description of the construction and operation of the same, reference being had to the annexed drawings, making a part of this specification, and to the letters and figures of reference marked thereon.

Figure 1 of the drawings is a sectional view of the barrel-head. Fig. 2 is a face view of the cutter. Fig. 3 is a vertical sectional view of the same, and Fig. 4 is a detail view.

This invention relates to machines for turning barrel-heads. In a machine constructed for such purpose the barrel-head to be turned is usually held between two rotary face-plates, capable of being opened or closed, so as to admit of the head being placed between them or removed after it has been turned. To effect the adjustment of one of the face-plates, so as to admit of the said insertion or removal of the head, a treadle and appropriate connections are employed. The saw and knives for cutting or paring the head, so as to give it the required marginal bevels, are carried by a shaft or arbor, which is rotated independently of the shaft carrying the face-plates and arranged to be swung around, so as to bring the saw and knives into position for operating upon the wooden barrel-head which is held between the face-plates. The shaft carrying the face-plates is turned by suitable gearing, so that when the saw and knives or cutters are revolved and brought into action one revolution of the face-plates carrying the head will be sufficient to finish the latter. Heretofore in machines of such character the concave saw has been employed for cutting the lower or broad bevel of the head while upon the knife-block, which is secured against the concave face of the saw, two sets of cutters of two each have been employed—one for cutting the upper or face bevel of the head and the small set for cutting the middle square edge between said two bevels. The objection to such arrangement is that the two knives or cutters

do not cut the face-bevel as smooth as is desired.

It is the object of my invention to obviate such defect, and to such end I provide between the cutter-block and the aforesaid concave saw a smaller intermediate saw for cutting the square edge between the two bevels. I employ four cutters upon the cutter-block, all adapted to cut or pare the edge of the barrel-head, so as to form the face-bevel of the same. These four knives perform the work more effectively than two, which latter number could only be used in machines heretofore constructed.

In the annexed drawings, A indicates a section of a barrel-head. a indicates the face-bevel; a' , the lower broad bevel, and a^2 the intermediate square edge. B designates a large concavo-convex circular saw. D is a small concaved circular saw fixed between the knife-block C and the large saw B. The block and saws are arranged upon the rotary shaft or arbor when applied to the machine and clamped together by means of a nut, E, which is tightened up against a collar or washer, F, located between the nut and the large saw. To the cutter-block are adjustably secured the four cutters, G, arranged in line and adapted to cut the face-bevel on the cask or barrel head. The cutters are slotted and held upon the sides of the block by means of bolts g , passing through their slots.

In operation the cutters pare or cut the head, so as to form the face-bevel a . The small intermediate saw forms the middle square edge and the large saw the under wide bevel. This is accomplished by swinging the shaft carrying the rotary face-plates between which the material to be operated upon is clamped around, so as to bring the edge of the blank at such an angle with relation to the saws and the cutters that both of the saws and the cutters will operate nearly at the same time, the smaller saw being the last to operate to cut the square edge a^2 of the barrel-head after the two bevels have been formed.

Having thus described my invention, what I claim is—

1. In a device for turning barrel-heads, the small concave circular saw arranged between

the large circular saw and the cutter-block, said smaller saw being adapted to cut the middle square edge of the head, substantially as specified.

5. 2. The combination, with the concave circular saw B, for forming the lower broad bevel of a barrel-head, of the smaller concaved saw for forming the middle square edge, and the cutters secured upon the cutter-block and

adapted to form the face-bevel of the said barrel-head, substantially as described.

In testimony that I claim the above I have hereunto subscribed my name in the presence of two witnesses.

W. M. J. SMITH.
